CLOTHES BRUSH

Elizabeth H. Lord, 487 Eastgate Road, Ridgewood, N.J.

Filed Apr. 8, 1964, Ser. No. 79,406

Term of patent 14 years

(Cl. D9—2)

FIG. 1.

FIG. 2.

FIG. 3.

FIG. 1 is a front elevation of a clothes brush showing my new design;

FIG. 2 is a side elevation thereof;

FIG. 3 is a bottom view thereof.

It is to be understood that the pattern of material shown partially applied on the drawing is intended to denote the material as an open mesh fabric and covers the entire area encompassed thereby, the article comprising a plurality of overlying plies of such material.

I claim:

The ornamental design for a clothes brush, as shown and described.
